UNITED STATES PATENT OFFICE.

MICHAEL EVANUK, OF TOTTENVILLE, NEW YORK.

ASTRONOMY DEVICE.

Application filed November 30, 1926. Serial No. 151,758.

This invention relates to a new and instructive device in the nature of a tellurian, particularly adapted to illustrate relative positions of the earth and sun.

5 The object of the invention is to provide an astronomy device of novel construction and arrangement of parts, hereinafter more fully described, claimed, and illustrated in the accompanying drawings, in which:

10 Fig. 1, shows a top plan view of my improved device.

Fig. 2, shows a side elevational view, partly in section so as to more clearly show the construction thereof.

15 Fig. 3, shows an enlarged sectional view taken on the line 3—3 of Fig. 2.

Fig. 4, shows a similar view taken on the line 4—4 of Fig. 2.

As here embodied my improved device 20 comprises an upright member 10, of hollow tubular construction, rotatively mounted in the support 11, attached to the disc member 11', adapted to enclose or cover the pit 14. The upright member 10 extends upwardly 25 therefrom in a vertical position. The spherical member 12, of hollow transparent colored material, preferably glass, or the like, representing the sun, is mounted on the upper extended extremity of the upright member 10.

An electric motor 13, of the commercial type is mounted in the pit 14, and is operatively connected by means of electric wires to an electric battery, or any convenient 35 source of electric power, not illustrated in the accompanying drawings. The worm 15 is mounted on the armature shaft of the electric motor 13, and meshes with a worm gear 16 mounted on the shaft 17, rotatively carried in the bracket 18, mounted in the pit 17. The bevel pinion 19 is mounted on the shaft 17, and meshes with the bevel gear 20, attached to the above mentioned upright member 10. The above described construction is 40 such as will permit the electric motor 13 to rotate or revolve the spherical member 12.

An electric light bulb 21, is mounted in a socket, of ordinary construction, positioned in the spherical member 12, and is connected 45 by means of the electric light wires 22 and 23, extended through the upright member 10, and are connected to any convenient source of electric current, so as to permit the electric light bulb 21, to illuminate the spherical member 12.

The bevel gear 24 is attached, intermedi-

ate, to the upright member 10, and meshes with a bevel pinion 25, attached to the tubular member 26, rotatively mounted in the bracket 27, attached to and extended from 60 the arm 28. The tubular member 26, is provided with an axial aperture, preferably of square cross-section, adapted to slidably receive the shaft 29, which is of similar cross section to engage therein, so as 65 to permit the tubular member 26 when rotated to rotate the shaft 29. The shaft 29 is slidably mounted in the block 30, rotatively mounted in the bracket 31 attached to, and extended from the upright member 32. The 70 shaft 29 is slidably mounted in the block 33, rotatively mounted in the bracket 34, attached to the carriage 35. The bevel pinion 36, is attached to the shaft 29, and meshes with a bevel pinion 37, rotatively mounted 75 on the vertically extended element 38, of the carriage 35. The tubular member 39, is attached to the bevel pinion 37. The universal joint 40, such as commonly employed, is attached to the closed upper extremity of the tubular member 39, and to the shaft 41, which extends upwardly 80 therefrom. The spherical member 42, representing the earth, is attached to the extended extremity of the shaft 41. The member 43', 85 made in the form of a frustum of a cone is of hollow construction and is attached to the carriage 38, and extends upwardly therefrom. The shaft 41, is positioned in the member 43', and extends beyond the base of 90 the said member. The above described construction is such as will permit the above mentioned electrical motor to rotate the spherical member 42, and which will permit the member 43' to cause the spherical mem- 95 ber 42 when rotated to travel, or rotate through a circular path, and assume the position designated by the reference numeral 42'. It should be understood that the shaft 41 lies upon the edge portion of the mem- 100 ber 43' and that as the shaft is rotated it rolls thereon and is guided in a circular path by the circular contour of said member 43'.

The arm 28 is attached, intermediate, the upright member 10, and extends outwardly 105 therefrom in a horizontal direction. The bevel pinion 43, is provided with an axial aperture, of square cross section, to slidably accommodate the shaft 29 so as to permit the shaft 29, when rotated to rotate the bevel pinion 43. The bevel pinion 44 meshes with the bevel pinion 43, and is attached to 110

the shaft 45, rotatively mounted in the upright member 32. The bevel pinion 46 is attached to the shaft 45, and meshes with the internal bevel gear 47, supported by the disc member 11', and attached thereto. The above described construction is such as will support the arm 28, and the above described elements attached thereto, so as to permit the upright member 10 when rotated to swing 10 the arm 28, in circular motion.

The support 48 is attached, at or near the extended extremity of the arm 27, and is provided with apertures, adapted to slidably receive the extended elements 49 and 50, of 15 the fork shaped member 51, pivotally attached, as at 52, by a pin or the like, to the above mentioned carriage 35. The wheel 53 is rotatively mounted on the shaft 54 carried in the carriage 35. The wheel 53, is 20 provided with flanged elements 55 and 56, adapted to engage the rail 57, which is formed or bent oval. The above described construction is such as will permit the spherical member 42, to travel, or rotate in an oval 25 path around the spherical member 12, as designated by the reference numeral 58. It is understood that the hereinbefore described tubular member 26, and shaft 29, are also provided for this purpose. The 30 gear ratios of the driving mechanism is preferably such as will cause the sphere 42 to rotate 364 $\frac{1}{4}$ times during each revolution thereof about the sun member.

It is obvious that I have provided a device which will clearly represent the movement and relative positions of the sun and earth.

Having thus described my invention, what I claim as new and desire to protect by 40 Letters Patent of the United States is as follows:

1. In a device of the class described a base comprising a substantially horizontal 45 platform, an elliptical track mounted on said platform, a circular track comprising teeth inscribed in said elliptical track, a vertical shaft rotatively mounted on said platform and extending therebelow substantially at the center of the ellipse bounded by 50 said track, a gear rigidly mounted on the lower end of said shaft and disposed below

said platform, a motor disposed below said platform, driving mechanism operatively connected with said motor and with said gear for rotating the latter, an extensible 55 arm attached at one end to said vertical shaft, a carriage comprising a wheel mounted on said track on the other end of said extensible arm, said carriage being adapted to be revolved through an elliptical path, an inverted hollow conical member mounted on said carriage, a shaft mounted on said carriage extending within said conical member, a bevel gear rotatively mounted on said shaft, a universal joint mounted on said bevel gear, a rod connected by said universal joint to said bevel gear and reclined upon the edge of said inverted hollow conical member, a sphere on the upper end of said rod and driving mechanism operatively connected with the teeth of said circular path for rotating said sphere during the elliptical revolution thereof, said rod being adapted to roll on the edge portion of said conical member for guiding the sphere in a circular 75 path at one and the same time.

2. In a device of the class described a base comprising a substantially horizontal platform, an elliptical track mounted on said platform, a carriage mounted on said track 80 adapted to be guided throughout an elliptical revolution thereby, an inverted hollow conically formed member mounted on said carriage, a stub shaft mounted on said carriage and disposed within said hollow conical member, a universal joint rotatively mounted on said stub shaft, an arm connected to said universal shaft and extending upwardly through said conically formed member engaging the edge portion thereof, 85 a sphere mounted on the upper end of said arm, and driving mechanism for simultaneously rotating said arm and the sphere thereon and revolving said carriage and sphere on said elliptical track, said arm being rolled on the edge of said conical member for guiding said sphere throughout a circular path.

In testimony whereof I have affixed my signature.

MICHAEL EVANUK.
